APPLICATOR

Herman B. Lermer, South Orange, N. J., assignor
to Celluplastic Corporation, Newark, N. J., a
corporation of New Jersey

Application October 24, 1947, Serial No. 781,798

7 Claims. (Cl. 128—261)

1

This invention relates to applicators, and more particularly to applicators such as are used for dispensing medicaments, jellies, pastes and other substances to body orifices, and the like.

The structure of the instant invention may be readily disassembled and re-assembled for cleaning and other purposes.

The invention is self-contained, the applicator parts having interengaging means to enable them to be assembled and disassembled at the will of the user, in a facile and rapid manner.

The foregoing, and other advantageous objects, which will later appear, are accomplished by the structure of my invention, of which certain embodiments are illustrated in the accompanying drawings. Modifications and other forms of the invention will become readily apparent from a consideration of said drawings and the description hereinafter; all other forms coming within the scope of the appended claims shall be deemed to be within the scope and purview of the invention.

In the drawings:

Fig. 1 is an elevational view of an applicator tube used in carrying out my invention.

Fig. 2 is an elevational view of a plunger member adapted to be reciprocated in said tube.

Fig. 3 is a transverse sectional view, taken on line 3—3 of Fig. 2.

Fig. 4 is a fragmentary, vertical, sectional view, taken on line 4—4 of Fig. 3.

Fig. 5 is a transverse sectional view, taken on line 5—5 of Fig. 2.

Fig. 6 is a foreshortened fragmentary, vertical, sectional view, taken on line 6—6 of Fig. 5.

Fig. 7 is a fragmentary, vertical, sectional view of the upper portion of an applicator embodying a modified construction of my invention.

Fig. 8 is a similar view.

Fig. 9 is a fragmentary, vertical sectional view, showing the applicator applied to a collapsible tube.

Fig. 10 is a fragmentary, vertical, sectional view of a modified form of the applicator.

Fig. 11 is a similar view of another form thereof.

Fig. 12 is a fragmentary elevational view of a further modification of my invention.

Fig. 13 is a fragmentary, vertical, sectional view of the form of invention shown in Fig. 12, showing the interengaging means of the plunger head and ring engaged.

Fig. 14 is a fragmentary elevational view of another form of applicator embodying the invention, and

Fig. 15 is a fragmentary, vertical sectional

2

view thereof, showing the interengaging means of the plunger head and ring engaged.

The tube and other parts of the applicator may be made of any suitable or convenient material, as, for example, a transparent or translucent thermoplastic or thermosetting material, preferably of such design as to provide for viewing the passage of material through the applicator tube.

10 Pursuant to the invention herein described, the applicator tube is provided with a collar fixed to the upper end thereof and having an aperture in which the plunger may be fully reciprocated, said aperture being of sufficient diameter to permit withdrawal therethrough of the plunger and the enlarged piston end thereof, for cleaning and other purposes. The upper end of the collar is closed by an open ring, the opening of the ring being sufficient to provide for free reciprocation 15 of the plunger therein but being of less diameter than the piston so as to normally preclude complete withdrawal of the plunger. The closure ring and collar are provided with complementary means to normally seat the ring in the collar.

20 As shown in Fig. 1, the applicator tube 10 is provided with an internally threaded cap 11 fixed to the lower end thereof, whereby the same may be secured to the collapsible tube 12 (Fig. 9) to initially fill the tube 10 with the material to be dispensed.

25 The assembled applicator of my invention comprises the parts shown in Figs. 1 and 2, the plunger 13 being positioned in the tube 10 and being adapted to be reciprocated therein. The closure ring 16 and collar 15 have complementary means (such as threaded portions as shown) to seat the ring in the collar. The ring 16 constitutes a guide for the plunger 13. The opening d' of the ring 16 is (Fig. 7) greater than the diameter of the plunger 13 but less than the diameter D of the piston 14 on the lower end of plunger 13, the piston 14 being of slightly smaller diameter than the internal diameter d of tube 10. The plunger 13 is provided at its upper end with a key head member 17. The latter is provided with a depending flange or circumferential rim 20. The key head member 17 and closure ring 16 are provided with any desired or convenient interengaging complementary means 18—19 for rotary movement of the head and ring simultaneously, such as key members or vanes 18 on the head member received within slots or keyways 19 of the closure ring 16, or vice versa. By virtue of said complementary keying means, it 30 will be apparent (see Fig. 7) that by registering the complementary keying means 18—19 and ro-

tating the head member 17 in a clockwise direction A (Fig. 7), said closure ring will be threaded into the collar 15 to prevent accidental withdrawal of the plunger 13 from the tube 10.

By rotating the plunger head 17 in a counter-clockwise direction, indicated by arrow B in Fig. 8, said closure ring 16 may be disengaged from the collar 15, so that the plunger 13 and its associated parts (see Fig. 2) may be withdrawn from the tube 10, to provide for complete cleaning, etc., of said parts. Thereafter, the applicator may be reassembled as above described.

In Figs. 10-15, there are illustrated other forms of the invention.

In the form shown in Fig. 10, the collar 25 secured to the upper end of the applicator tube 26 is externally threaded as at 27, to be threadedly engaged by the complementarily threaded portion 28 of the closure ring 29. The opening 30 of the ring 29 is of greater diameter than the plunger 31 but is of less diameter than that of the piston secured to the lower end thereof.

It will be understood that the piston 14 of Fig. 2 is secured to the lower end of the plunger 13. In the various forms illustrated in Figs. 10-15; a showing thereof has been omitted in the last mentioned figures to avoid needless duplication in the drawings.

The plunger 31 has secured to the upper end thereof a head 32, said head and ring being provided with complementary interengaging keying means 33-34 which are adapted to seat the ring 29 on the collar 25 when the head 32 is rotated in one direction, and to provide for disengagement thereof when the head is rotated in an opposite direction.

In form shown in Fig. 11, the applicator tube 35 has a collar 36 secured to the upper end thereof, said collar having an aperture 36a and an internally stepped portion 37. The ring 39 is provided with a complementarily stepped portion 38 adapted to frictionally fit within the stepped recess 37 of the collar 36 to normally frictionally seat said ring in the collar. The ring is provided with rim 40 projecting beyond the circumference of the collar 36. The rim 40 may thus be readily grasped to forcefully remove the ring from its seat in the collar, when so desired, to provide for complete withdrawal of the plunger from the tube. The plunger 41 is provided with a head 42 for facility of operation of the plunger.

In the form shown in Figs. 12 and 13, the tube 43 has a collar 44 secured to the upper end thereof, said collar having a stepped, recessed, portion in which the complementarily portion 46 of the ring 47 may be frictionally seated. The plunger 23 has secured to the upper end thereof the head 48. The ring 47 and head 48 are provided with complementary interengaging means to permit the withdrawal of the ring 47 physically from the seat of the collar. Said keying means may comprise a bayonet-slot arrangement 49-50.

In the form shown in Figs. 14 and 15, the ring 51 is seated in the collar 52, and the head 53 is secured to the upper end of the plunger 54, the ring and collar being provided with complementary interengaging means comprising bayonet-slot members 55-56; in the form shown in Figs. 14 and 15, the pins 56 are secured to the ring 51 and the slots 55 are disposed in the head member, whereas, in Fig. 12, the reverse arrangement is shown.

The drawings show (Figs. 1-9) the cap 11 and collar 15 as separate units secured to tube 10, but

they may be molded with the tube 10 so as to define therewith a single article of the combined general outline of the three separate parts (tube 10, cap 11 and collar 15). Similarly, the plunger 13, key head 17 and piston 14 may be molded as a single article, if so desired, or may be formed as shown in the drawings of the three separate parts secured together in any desired or convenient manner. The corresponding parts, shown in Figs. 10-15, may be similarly formed.

It is noted that the collar 15 is fixed to the tube 10 permanently. Likewise the collars 25, 36, 44 and 52 are permanently fixed to the tubes 26, 35, 43 and 51, respectively. All of the rings 16, 29, 38, 46 and 51 are detachable from their associated collars.

Having thus described my invention, what I claim as new and desire to secure by Letters Patent is:

20. 1. An applicator comprising an elongated tube, a collar permanently fixed to the upper end of said tube, a closure ring detachably secured to said collar, a plunger slidably disposed in said ring, said plunger having a piston on one end thereof and a head on its other end, said ring having an aperture of greater diameter than the plunger but of smaller diameter than the piston, said ring and collar each having complementary securing means thereon to detachably secure the ring on the collar, said head and said ring each having complementary interengageable means thereon arranged respectively in opposed relation to each other whereby said collar and said ring may be readily assembled and disassembled.

2. An applicator comprising an elongated tube, a collar fixed permanently on one end of the tube, a closure ring, said collar and ring having interengageable complementary screw threads 40 thereon whereby said collar and ring may be detachably secured together, a plunger movably disposed in said tube and slidably guided in said ring, said plunger having a head on one of its ends and a piston on its other end, said head and said ring each having interengagable means 45 thereon arranged respectively in opposed relation to each other whereby said head and said ring may be rotated as a unit when said means are interengaged to readily disassemble said ring from said collar.

3. The construction set forth in claim 2 in which the collar is externally screw-threaded and said closure ring is provided with internally located screw threads cooperating with said 55 threaded collar.

4. The construction set forth in claim 2, in which the collar is provided with internally located screw-threads and the closure ring is provided with externally located screw threads 60 cooperating with the screw threads of said collar.

5. The construction set forth in claim 2, in which the head is provided with radial vanes, said closure ring being provided with radial recesses adapted to selectively receive said vanes, 65 said vanes and said recesses being arranged respectively in opposed relation to each other.

6. The construction set forth in claim 2, in which the head is provided with substantially housed vanes, said closure ring being provided 70 with radial stop portions arranged in opposed cooperative relation to said vanes.

7. An applicator comprising an elongated tube, a collar permanently fixed on one end of said tube, a closure ring for said collar, said collar 75 being internally screw-threaded, said closure

ring being removably threadedly fitted in said collar, a plunger disposable in said tube and slideable through said closure ring, said plunger having a head on one of its ends and a piston on its other end, said head and said ring each having interengaging means thereon respectively, the means on said head and the means on said closure ring being arranged in cooperative opposed relation whereby said head and said closure ring may be interengaged for rotative movement as a unit to effect separation of said ring from said collar.

HERMAN B. LERMER.
